ATTORNEY

UNITED STATES PATENT OFFICE.

JOHN N. WELLS, OF LOWER LAKE, CALIFORNIA.

CIGAR-HOLDER.

1,295,652.

Specification of Letters Patent. Patented Feb. 25, 1919.

Application filed August 10, 1917. Serial No. 185,540.

To all whom it may concern:

Be it known that I, JOHN N. WELLS, a citizen of the United States, residing at Lower Lake, in the county of Lake and State of California, have invented new and useful Improvements in Cigar-Holders, of which the following is a specification.

This invention relates to a cigar holder and the primary object of the invention is to provide an article of manufacture of this character which is in the form of a sectional casing to enable a cigar when arranged therein to be smoked without likelihood of the ashes disfiguring the clothing of the wearer and also to enable a whole, or partially consumed cigar to be carried within the pocket without the cigar becoming cracked or broken.

Another object of the invention is to provide one of the casing sections with a spring clip which may not only be employed to retain the cigar engaged with one of the casing sections but may also be employed to engage the casing with the wall of a pocket in the clothing of the owner of the holder.

With these and other objects in view, the invention resides in the novel combination and arrangement of parts, which will be hereinafter described and particularly pointed out in the claim.

The preferred embodiment of the invention has been illustrated in the accompanying drawing, although no restriction is necessarily made to the precise details of construction therein shown, as changes, alterations, and modifications, within the scope of the claim may be resorted to when desired.

In the drawing:

Figure 1 is a view in side elevation of a cigar holder constructed in accordance with the invention.

Fig. 2 is a longitudinal sectional view therethrough.

Fig. 3 is a similar view showing the clip upon one of the sections raised to permit the disconnection of the cigar from the section.

Fig. 4 is a vertical transverse section on the line 4—4 of Fig. 3.

Like characters of reference denote corresponding parts throughout the several views in the drawing.

Referring now to the drawing in detail the numeral 10 designates a casing in which may be arranged a cigar 11 with the casing formed from a pair of casing sections 12 and 13. The casing section 12 which is of less

length than the casing section 13 is provided at one end with a reduced extension 14 having extending longitudinally thereof a channel 15, which is enlarged for a portion of its length, as at 16 to enable the end of the cigar to be inserted in the casing section 12. The casing section 12 which serves as a mouth-piece has formed in the body thereof a longitudinally extending recess 17 in which is arranged a leaf spring 18 having one end thereof secured to the casing section and its other end provided with an actuating knob 19. The leaf spring has secured to its under face a curved pin 20 which passes through a hole 21 in the casing section and extends within the enlarged portion of the channel 15 to engage the end of the cigar inserted in the channel and retain the cigar in engagement with the casing section 12.

The casing section 13 overlaps an end of the casing section 12 with the overlapping portion of the casing section 13 threadedly connected with the underlying portion of the casing section 12, the outer end of the casing section 13 has stretched there across a wire netting 23 which, prevents the ashes which fall from an ignited cigar escaping from the holder.

When it is desired to employ the holder to protect a cigar to be carried in the pocket, the casing section 13 is disconnected from the casing section 12 and the spring 18 raised to withdraw the pin 20 from the channel 15, so that the end of the cigar may be inserted in the casing section 12. Pressure by the fingers upon the spring is now released to allow the spring to drive the pin 20 within the cigar and the casing section 13 can now be connected with the casing section 12. When the casing sections have been connected as described the holder is arranged in the pocket with the front wall of the pocket passing between the knob on the spring and casing section 12, thus the clip prevents the casual displacement of the holder from within the pocket.

When it is desired to smoke the cigar within the holder the casing section 13 is disconnected from the section 12 and the cigar ignited after which, the casing section 13 is again engaged in the casing section 12 to prevent the ashes or sparks from the cigar disfiguring the clothing of the smoker.

From the foregoing description, taken in connection with the accompanying drawing, it is at once apparent that a cigar holder has

been provided which is comparatively inexpensive to manufacture and efficient in the purpose set forth.

Having thus described the invention, what is claimed as new, is:—

A cigar holder comprising a casing terminating in a mouth piece and provided with a recess receiving a cigar, a leaf spring secured at one end upon said casing, and 10 a pin secured upon the underside of said

spring at a point spaced from its free end and extending through a hole in said casing, for penetrative engagement with the cigar, the free end of said spring being formed as a knob, and the portion of said spring between 15 its free end and said pin serving as a garment pocket engaging clip.

In testimony whereof I affix my signature.

JOHN N. WELLS.
